(57) **CLAIM**

I claim the ornamental design for a wobbling balance board, as shown and described.

DESCRIPTION

FIG. 1 is a top, front, right isometric view of my new design for a wobbling balance board;

FIG. 2 is a bottom, rear, left isometric view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

1 Claim, 4 Drawing Sheets

FIG. 1

FIG. 2

FIG. 3

FIG. 4

FIG. 5
